(57) **CLAIM**

The ornamental design for a piano key overlay tile as shown and described.

DESCRIPTION

FIG. 1 is a front perspective view of a piano key overlay tile according to one embodiment of the new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a front view of a piano key overlay tile according to another embodiment of the new design;

FIG. 9 is a back view thereof;

FIG. 10 is a left view thereof;

FIG. 11 is a right view thereof;

FIG. 12 is a top view thereof;

FIG. 13 is a bottom view thereof;

FIG. 14 is a front view of a piano key overlay tile according to another embodiment of the design;

FIG. 15 is a back view thereof;

FIG. 16 is a left view thereof;

FIG. 17 is a right view thereof;

FIG. 18 is a top view thereof; and,

FIG. 19 is a bottom view thereof.

The piano key overlay tile is shown with symbolic breaks in its length. The appearance of any portion of the article between the break lines forms no part of the claimed design.

1 Claim, 3 Drawing Sheets

Related U.S. Application Data

continuation of application No. 29/625,373, filed on Nov. 9, 2017, now Pat. No. Des. 888,151.
